WILLIAM T. BENHAM, OF NORWOOD, OHIO, ASSIGNOR TO THE NYDIA BANK LOCK COMPANY, OF CINCINNATI, OHIO, A CORPORATION OF OHIO.

TUMBLER MECHANISM FOR PERMUTATION LOCKS.

1,195,766.

Specification of Letters Patent. Patented Aug. 22, 1916.

Application filed December 4, 1915. Serial No. 65,115.

To all whom it may concern:

Be it known that I, WILLIAM T. BENHAM, a citizen of the United States, residing at Norwood, in the county of Hamilton and State of Ohio, have invented new and useful Improvements in Tumbler Mechanism for Permutation-Locks, of which the following is a specification.

My invention relates to combination locks, 10 and particularly to improvements in the tumblers for such locks and the means of operating and setting the same.

There are two general types of tumblers, 15 called, respectively, key-changing and hand-changing. The former can be set only when the tumblers are in their position on the stump. The hand-changing tumblers, must be removed from the stump when the combination is being changed and the tumbler 20 itself taken apart in order to reset it.

I show, in the improvements herein described, an improved tumbler mechanism so constructed that the combination may be set up without removing the tumblers from the 25 stump, or the tumblers may be removed and set up separately without taking any tumbler apart, so that it has all the advantages of both the key-changing and the hand-changing types.

30 There is a further convenience in my device in that all tumblers may be made exactly alike, so that they do not need to be numbered and set up each time on the stump in the same order.

35 The tumbler casing is also of an improved construction. The changing key is operated through the regular slot in the tumbler casing which the angle bar enters. The tumbler casing is formed of two cupped disks 40 that telescope one within the other.

This invention is particularly adapted for use with a dial numbered as shown in U. S. Letters Patent #1,113,865, issued to me, October 13, 1914; and each of the tumblers 45 is preferably also numbered both clockwise and contra-clock-wise from zero.

The propellers are all alike. Therefore, any propeller may be used with any tumbler, and the propellers are separate elements seated upon the stump like the tumblers instead of being a part of the tumbler.

My invention is illustrated in the accompanying drawings, in which:

Figure 1 is a nest of three tumblers set up 55 ready for use. Fig. 2 is a plan view of one

of the tumblers. Fig. 3 is a view of the smaller element of the tumbler casing open and with the mechanism in place. Fig. 4 is an axial section through the tumbler casing and its central disk, with the spring and clamping jaws removed. Fig. 5 is a back view of the rosette. Fig. 6 is a perspective view of one of the combined propellers and spacing washers. Fig. 7 is one of the friction washers used between the tumblers, mounted on the stump shown in section. Fig. 8 is the key that holds up the angle bar of the lock and spreads the automatic clamping jaws in the tumblers.

Referring now to the drawings, R designates the "rosette", provided with the usual extended axial "stump", r, preferably integral therewith. Upon the stump are tumblers, A, adjacent to each of which is a combined "propeller" and spacing washer, consisting of an annulus, P, provided with a lug, p, extending at one side of the annulus parallel with its projected axis. When in position, the lug, p, projects through an arc slot, b³, in the central disk, B, of the tumbler, A. Annular friction washers, W, having centripetal projections, w, engaging in corresponding key slots of the stump, r, are preferably employed between each "propeller" and its tumbler and between the propeller and the next tumbler in series; and a holding washer, W², is secured at the end of the series of tumblers and "propellers" by a set screw, T, in the end of the stump.

Each tumbler, A, consists of a central disk, B perforated to fit rotatively upon the stump, r, and an outer annular casing, A¹, fitting exteriorly upon the periphery of said disk. The said outer casing, A¹, consists of two similar members, a¹, a², fitting together telescopically to form a shallow annular casing seated centripetally upon the periphery of the disk, B, at the sides, respectively, of a central peripheral enlargement or rib, b, serrated with teeth, b², marking the unit fractions of a complete revolution used on the tumbler system of the lock. Corresponding markings are placed on the outer side of the casing member, a¹, at the line of contact with the disk, B,—all as shown in Fig. 2.

The inner casing element, a¹, is provided with two pivotal clamping jaws, C, C, extending at the sides of the central disk, B, respectively, each jaw having at the contact space with the serrated rib, b, a correspond-

ing series of teeth, c , so that when the jaws are moved toward each other the teeth engage and hold the casing element a , and disk, B , against inter-rotation. The pivots 5 of the jaws, C , C , extend outwardly into engagement with both sides of the casing.

The clamping jaws, C , C , are normally held in engagement with the disk, B , by springs, S , fitted to rest against the outer 10 wall of the element, a^1 , and contacting tangentially against the back of the clamping jaws, respectively, as shown in Fig. 3. I prefer to construct these springs, as shown, 15 as terminals of a single strip curved centrally to rest against the outer wall of the casing.

The forward ends of the clamping jaws, C , C , are brought to near contiguity in a suitable recess, a^3 , cut through the outer 20 walls of both casing elements, a^1 , a^2 ; so that by the insertion of a suitable spreading key, K , between the terminals of the clamping jaws, C , C , in all the tumblers, the tumblers may all be reset as desired and upon withdrawal 25 of the spreading key the parts automatically engage and are thereafter held in the new relation until again reset. A mark, b^4 , upon the side of the disk, B , at the periphery radially opposite to the arc slot performs the usual function in setting the 30 tumblers of the stump.

A pin on the drive tumbler (not shown) contacts with the propeller lug, p , at the free 35 end of the stump for rotating the tumblers and working the combination in the usual way.

A spreading key, K , is employed, provided 40 with a rib, k , to hold the angle bar of the lock mechanism out of the tumbler slot formed by the outer recesses of the casing 45 into which the clamping jaw terminals, C , C , project (Fig. 3), while the combination is being changed with all the tumblers on the stump. The key has a pointed end to aid in spreading the several clamping jaws as it is pushed into and through the casing recesses and between the terminals of the clamping 50 jaws.

When the combination is changed while 55 the tumblers are on the stump, the key is inserted through the key hole r^1 of the rosette R . (Fig. 6.)

I claim as my invention and desire to secure by Letters Patent of the United States:

55 1. A tumbler for permutation locks embodying a central disk provided with a toothed annulus upon its periphery; an outer annular casing composed of two similar cup-shaped elements held together by 60 telescopic fit of their outer walls one within the other, said elements abutting at their

inner edges against the periphery of the central disk at the sides of the toothed annulus; and adjustable means secured to and within the hollow casing immediately adjacent to 65 the toothed annulus, and adapted to engage directly therewith to prevent inter-rotation.

2. The combination in a permutation lock, with the toothed central disk and annular casing of a tumbler, of a pair of clamping 70 jaws each pivoted at one end to the casing and extending thence tangentially adjacent to the central disk at opposite sides thereof, and provided with engaging teeth at the near side; and a spring, seated against the 75 peripheral wall of the casing and normally bearing directly upon the back of each jaw opposite its place of engagement with the toothed disk to maintain said engagement.

3. In a tumbler for permutation locks, the 80 combination of the toothed central disk; the annular outer casing having a single peripheral slot; and the toothed clamping jaws arranged to register with said slot, as shown; with a single key adapted by insertion to release 85 the clamping-jaw connection of the disk-elements, and lift the angle bar, at the same time.

4. In a tumbler such as described, the combination of the toothed disk and casing, the 90 toothed clamping jaws pivoted in the casing at opposite sides of and adjacent to the toothed central disk and a single curved spring seated within and against the outer walls of the casing and bearing inwardly 95 near its ends against the jaws.

5. A tumbler body for permutation locks embodying in combination a central disk having a peripheral flange of reduced width, and an external casing fitting upon the 100 shoulders thus formed and consisting of two annular cup-shaped elements held together by telescopic fit of their outer cylindrical walls.

6. In a permutation lock, in combination 105 with a series of tumblers each having a central disk with a segmental perforation, of a corresponding series of propellers each consisting of an annulus adapted to fit upon the stump adjacent to a tumbler and provided with a lateral finger or "dog" peripherally attached to the annulus and adapted to extend through the adjacent tumbler into contact engagement with the similar finger or dog of the next tumbler in series. 110

In testimony whereof I have hereunto set my hand in presence of two subscribing witnesses.
